UNITED STATES PATENT OFFICE.

TIMOTHY NEWELL, OF PARKDALE, OREGON.

SORTING MACHINE.

Application filed December 15, 1920. Serial No. 430,816.

To all whom it may concern:

Be it known that I, TIMOTHY NEWELL, a citizen of the United States of America, and resident of Parkdale, in the county of 5 Hood River, in the State of Oregon, have invented certain new and useful Improvements in Sorting Machines, of which the following is a specification, reference being had to the accompanying drawings.

10 My invention relates to apparatus for sorting and dividing a mass of articles of one kind but of different sizes into separate groups, each group to be composed of individual articles all approximately uniform 15 form as to size.

A distinctive object of my invention is to promote the speed and accuracy of the sorting operation. Another is to provide, in a machine of the class described, means 20 for segregating articles one from another individual according to size as determined by the weight of each article. A further object of my invention is to provide a machine of the kind described for separating 25 and delivering, in one continuous operation, individual articles into receptacles provided severally for the reception of articles of a predetermined range of size.

My invention, in present preferred form 30 of embodiment, as illustrated in the accompanying drawings comprehends means for accomplishing, along with other objects, the objects above indicated; but in respect to mechanism for selecting and distributing 35 articles by weight from a continuing feed of articles in individual succession, the form illustrated is only preferential, inasmuch as the principle of my invention may be embodied in what appears to be widely different 40 mechanisms, but which prove, upon close analysis, to be, as will be in some instances indicated, all united by a common tie.

Objects of my invention in addition to those specified above, are various as will 45 appear from the following description.

What constitutes my invention will be hereinafter specified in detail and succinctly set forth in the appended claims.

In the accompanying drawings, Figure 50 I is a side elevation of the selective or sorting mechanism of my machine to which in the completed machine is also joined in endwise assemblage feeding mechanism as shown, for example, in Figure II.

Figure II is a sectional view of my feed- 55 ing mechanism, taken as on the line II—II of Figure IV.

Figure III is a top plan view, with parts broken away, of the subject matter of 60 Figure I.

Figure IV is a top plan view of the feeding mechanism complete, of which, in Figure II, a part is shown in section.

Figure V is a transverse section on the line V—V of Figure VI, looking from left 65 to right.

Figure VI is a side elevation of the subject matter of Figure IV.

Figure VII is a transverse section on the line VII—VII of Figure VI, looking from 70 right to left.

Figure VIII is a section on the line VIII—VIII of Figure III, looking from left to right, and drawn to enlarged scale.

Figure IX is a view on reduced scale 75 corresponding to Figure VIII in part, but showing a modification of my invention.

Figure X shows in a similar view a further modification.

Referring to the numerals on the drawings, 1 indicates an extended oblong frame whose length, dimensions and general construction need not conform to any particular rule, but may be made in the builder's discretion to correspond to the size of the machine and the work required of it. Owing to the limitations imposed by the size of the drawings, the frame 1 is not shown complete as to length in any single figure of the drawings, but the reader will have no difficulty in apprehending its longitudinal extent if upon comparison of Figures I and II, for example, he will bear in mind that the complete machine embodies in one the parts represented by those two figures joined together, end to end, their points of separation being shown to the extreme left of Figure I and to the extreme right of Figure II.

The driving power of the entire machine 100 is, from a source of power not illustrated, preferably communicated to a shaft 2 revolvably mounted in suitable bearings 3 on the frame 1, and rotative as by means of a pulley 4 secured to said shaft (compare 105 Figs. I and VI). As shown, the shaft 2 is horizontally disposed in operative relationship to a vertical shaft 6 carried in suit-

able bearings 7 and 8 provided for it in the frame 1, the shaft 2 being preferably provided with a worm 10 that is fixed to it and which meshes with the worm-gear 11 fixed to the shaft 6.

The shaft 6 is preferably extended through its upper bearing 8 and has fixed to it, above a table 12, a sprocket gear-head 14 about which is bent an endless sprocket chain 15 which is stretched into like operative engagement with a sprocket gear-head 16 rotatably mounted in any preferred manner upon the table 12, as, for example, in a suitable bearing 17 provided for the accommodation of a vertical stud-shaft 18 and located at the end of the table 12 opposite to that which carries the gear-head 14. The shaft 18 may be made rotative in its bearing 17 or it may be fixed so as to accommodate upon it the gear-head 16 in rotative relationship to it. The determinate length of the endless chain 15 determines the length of the table 12, and, in so far, determines the length of the frame 1.

As is clearly shown in Figure V, the shaft 6 carries, at a convenient distance above its bearing 7 and between the bearings 7 and 8, a crown gear 20 that is fixed to it. The crown gear 20 meshes with the pinion 21 that is fixed to a shaft 22 carried in suitable bearings 23 on the frame 1 and in parallel relationship to the shaft 2. The shaft 22 also carries a pulley 24 fixed to it that communicates motion as by a belt 25 to a pulley 26 fixed to the end of a horizontal shaft 27 that is carried in suitable bearings 28 and 29 on any suitable members of the frame 1 that may be conveniently disposed for their accommodation.

Upon its end that is opposite to the pulley 26 and nearer to the bearing 29, the shaft 27 carries in fixed relationship to it two sprocket-gears 30 and 31. About the gear 30, and in mesh with it, is bent an endless sprocket-chain 32, and about the gear 31 is bent an endless sprocket-chain 34 of length corresponding to that of the chain 32. The chains 32 and 34 are carried in parallel relationship as shown for example, in Figure IV by aid of sprocket-gears provided for their respective accommodation on the frame 1 near the end thereof that is furthest removed from the gear-head 16. A shaft 35, mounted in suitable bearings 36 provided for it near the last aforesaid extremity of the frame 1, carries a pair of sprocket-gears 36 and 37 (compare Figures II and VII). The gears 36 and 37 are spaced apart to correspond to the spacing between the sprocket-gears 30 and 31 and constitute in effect guide pulleys to the chains 32 and 34 with which they mesh so as to hold said chains in parallel relationship. The distance between the shafts 27 and 35 is insufficient to draw the chains 32

and 34 taut about their respective sprocket-gears, but is such as to accommodate a slackness of the chains between those shafts which is taken up by an intermediate shaft 40. The shaft 40, being also mounted in suitable bearings provided for it upon the frame 1, carries a pair of spaced sprocket-gears 41 and 42 whose office is to guide the chains 32 and 34 with tautness in their travel about the shafts 27 and 35, as well as the shaft 40. The location of the shaft 40 is preferably nearer to the shaft 35 than to the shaft 27 so as to impart to the chains 32 and 34 a triangular disposition as is shown in Figure II. The purpose of the location of the shaft 40 just referred to is to divide the upper reaches of the chains 32 and 34, respectively, into a level display stretch measured by supporting strips 43 and an inclined plane represented by supporting strips 44. The function of the said strips 43 is to hold the chains 32 and 34 in substantially horizontal or level assemblage between the shafts 27 and 40. The function of the strips 44 is likewise to hold the chains 32 and 34 in a uniform plane of inclination between the shafts 35 and 40. The particular purpose of the presentation of the chains 32 and 34 in two modes, one horizontal and the other inclined as specified, will be hereinafter more fully set forth.

At regular intervals, oppositely disposed links of the respective chains 32 and 34 carry angle-plates 45 (see Figure VII) for the accommodation between them of a lifting member that is preferably a roller 48. The regular succession of rollers with which the chains 32 and 34 are provided, is well illustrated in Figures II and IV as well as in Figure VII.

Upon the end of the frame 1, in operative proximity to the shaft 35, I provide a hopper 49, having an inclined bottom 50 secured in hinged relationship to the hopper, as by the horizontal hinge 51 (Figure II). The vertical front wall 52 of the hopper 49 defines, above the free end of the bottom 50, a discharge opening 53, which is provided with a vertical sliding gate 54 by whose adjustment discharge of articles from the hopper 49 in the direction of the shaft 35 may be regulated. Secured at one end to the free end of the bottom 50, as indicated at 56, I prefer to employ an oblong flexible strip 57 which, from its line of juncture 56, extends over the rollers 48 substantially the full length of the strips 44 and 43, respectively, its end opposite the line 56 being in like manner secured, as indicated at 58, to a cross-strip 59, extending between chute-defining side walls 60 and 61 that are disposed adjacent to the opposite ends of the respective rollers 48. A distinctive quality of the strip 57 is a high degree of flexibility, wherefore, a

woven fabric may be used as the material for the strip, but I prefer to make it of netting having a large, open mesh like a fish net, and made of medium sized twine are adapted to receive such defective articles as may be culled by an attendant from those presented in mass for his inspection upon the strip 57.

5 of the kind used in making fish nets. The strip should be of length sufficient to permit of a preferably decided sag of material between each roller 48 and the one adjacent to it on either side. It is the presence of the said sag between rollers that makes it operative, but naked rollers may be used without the strip by using a little closer relative disposition of the rollers. If the strip 57 is used it will itself suffice to prevent escape of articles between the rollers 48; but if the strip be dispensed with, the rollers must be close enough together to support the articles in rolling contact thereupon.

10 The mechanism above described relates in the main to the feeding mechanism of my machine, so called because it is that which is designed and adapted to feed articles to the sorting mechanism, whereof the sprocket gear-heads 14 and 16, with their connecting sprocket-chain 15, have already been specified.

15 The endless sprocket-chain 15, driven, as it is, above the table 12 in an orbit fixed to the driving gear-head 14 and by its companion gear-head 16, is made up of a series of links of suitable and preferred form and assemblage, each link at suitable intervals being provided with a fulcrum-support 75.

20 The chains 32 and 34 united by lifting members or rollers 48 constitute an endless flexible strip 57, serves to segregate articles supplied to it from the hopper 49 and to roll them from the point of their initial delivery to the strip 57 which is adjacent to the shaft 35 towards the place of their discharge from the conveyor, which is adjacent to the shaft 27 and is determined by the presence of the cross-strip 59. It is found, in practice, that the action of the lifting members 48 is efficient to carry the articles up an incline, as represented in Figure II by the inclination of the strips 44. The function of the member 75 is to afford a delicate pivotal or balance support to a balance member or beam 76. To that end, it is preferably bifurcated, as shown in Figure I, to accommodate between its bifurcations a downwardly projecting lug 77 upon the beam. Each beam is provided at one end with a scale 80 whereof there is a continuous succession of individuals disposed in parallel relationship and close juxtaposition upon the sprocket-chain 15. Each scale is preferably made in the form of a slightly transversely curved trough, having a smooth surface and unobstructed from end to end. To give it freedom from

The cross-strip 59 is obliquely disposed to the side walls 60 and 61 between which it extends and by which it is supported, and serves to guide the discharge of articles to an endless conveyor belt 63 that is stretched about pulleys 64 and 65. The pulley 65 is secured to the shaft 40 (see Fig. VII) and derives rotative motion from the engagement between the sprocket-chains 32 and 34 and the sprocket-gears 42 and 41 thereon.

terminal obstruction, its longitudinal axis 100 is preferably disaligned from that of the beam 76, as shown in Figure VIII. The end of the beam 76 opposite the scale 80 is provided with a counterpoise 81 which is preferably truncatedly conical in shape. It 105 may be adjustable endwise of the beam 76, but is preferably permanently secured thereto as illustrated. The weight of the counterpoise 81 is calculated not only to hold the scale 80 in horizontal disposition, 110

I prefer to provide in parallel relationship to the conveyor belt 63 a like conveyor belt 67 which passes around the pulley 65 and is driven by it, being held taut against it by the pulley 68. The conveyor belt 67 extends practically the full length of the frame 1, its purpose being to receive, at any point along the length of a machine, the deposit of an article, and to convey all articles so received to a place of common discharge. The conveyor belts 63 and 67 are provided with outside guard rails 61 aforesaid and 70, and an intermediate guard rail 71 which serve, collectively, to define transversely the operative limits of the two conveyor belts on either side, and effectively to separate one from the other.

but also to balance the critical weight of an article when placed in the scale 80 in predetermined juxtaposition to the fulcrum support 75. It is obvious that an article of given weight will tend, in proportion to the distance of its location in the scale 80 from the fulcrum support 75, to tilt the beam and thereby cause gravity to discharge from the free end of the scale the contents thereof. Therefore, if an article exceeding in weight a predetermined critical weight be placed in the scale 80, and in predetermined proximity to the fulcrum support 75, it will cause the beam 76 to tilt, with the effect of discharging the article from the scale. If the article placed in the scale 80 be of less than the critical weight,

65 Adjacent and in parallel relationship to the conveyor belts 63 and 67, I prefer to provide inclined bulk-chutes 73 and 74 that movement thereof in the scale in the direction away from the fulcrum support 75, will, through increase of leverage, so de- 130

- rived, as soon as such leverage is sufficient, to overcome the weight of the counterpoise 81, and effect discharge of the article from the scale. The lighter the weight of the article placed in the scale the greater must be the distance of its removal from the fulcrum support 75 before it will tilt the beam 76 against the weight of the counterpoise 81 and effect discharge from the scale.
- 10 It is upon the principle just elucidated that the sorting mechanism of my invention operates. That principle consists in the shifting, in effect, of the fulcrum support 75 of the beam 76. By my invention, 15 in the preferred form of embodiment illustrated, the relative position of each fulcrum support with respect to its beam is made constant, and the weighing effect of the beam is attained by variation of the distance of the article to be weighed from the fulcrum support; but, obviously, the weighing effect is the result to be reached, and that may be accomplished by relative variation of the fulcrum, the weight and the 20 article to be weighed. For example of such variation, I illustrate in Figure IX one form of modification, in which a beam *a*, corresponding in function and assemblage to the beam 76, is provided with a scale *b*.
- 25 The beam *a* is slidable longitudinally through a sleeve fulcrum-piece *c* provided for it, and corresponding in function to the fulcrum-support 75. The beam *a* is provided with a head *d* and between the head *d* and the sleeve *c* with a spring *e*. The head *d* is preferably capped to carry an antifriction ball *f*, which, riding against an oblique guide plate *g*, serves, through the obliquity of disposition of the plate *g* 30 to the series of beams *a*, gradually and successively to shove the scale *b* of each beam *a* away from its sleeve fulcrum piece until the scale is made to tilt by the weight of its load, and thereby to discharge its load.
- 35 The modification shown in Figure X includes a beam *a'* having an outthrusting spring *b'* for actuating a telescope extension *c'*.
- I prefer to provide for the attainment of 40 the purposes of my invention through the coaction of two movements of the article to be weighed. One is movement thereof longitudinally within the scale 80, and the other is a movement gained by the shifting 45 of the position of the scale itself. By this contrivance, each one of the series of scales 80 is made to discharge its contents according to the weight thereof when the scale shall have reached a substantially determined point in its orbit of travel communicated by the sprocket-chain 15.
- For the grading of apples, for instance, uniformity of size for commercial purposes is that in which there is substantial uniformity of weight, or, in other words, equivalency
- of weight between ascertained limits. Absolute uniformity of weight would require each scale to discharge its contents upon reaching, in its orbit of travel, a certain point, accurately predetermined. This, by 50 the aid of my invention, is indeed practicable, but, to make it available in practice, would require an unnecessary multiplication of receptacles for the fruit discharged by the several scales and would render the 55 operation of the machine too slow for ordinary commercial service. For commercial purposes, it is not necessary to grade the fruit to a degree even approximating absolute accuracy. A slight variation in the 60 weight thereof is, for obvious reasons, not only permissible but desirable. A small variation in weight, say perhaps of an ounce or certainly a fraction thereof, is not discernible to the eye in the grading of such 65 fruit as apples. Consequently, it is sufficient in ordinary practice to provide for the reception of the fruit such a number of bins 70 as may be necessary to effect the grading of the fruit desired. In the drawings (see 75 Fig. III, for example) duplicate sets of bins are shown, each set containing six bins. Provision is therein made for the sorting of apples into six grades, each bin being approximated to apples in which the actual 80 weight may vary slightly within predetermined limits, but not enough to violate the rule of grading prescribed. In Figure III of the drawings, each bin 83 is shown as 85 designed to receive the discharge of four consecutive scales 80, but obviously it might be made to receive the discharge of a greater or a less number of scales, according to the 90 accuracy of grading desired.
- The travel of the scales 80 in consecutive 95 order and in a prescribed orbit being attained as specified for example by the movement of the sprocket-chain 15, the gradual movement of articles longitudinally through the scales of the series, respectively, is preferably secured by the aid of a movable member disposed obliquely to the series of scales and having its movement synchronized to that of the sprocket-chain 15. To that end I prefer to extend the shafts 6 and 18 upwardly a sufficient distance for the accommodation of horizontal pulleys 85 and 86, the pulley 85 being driven by the shaft 6 to which it is fixed. An endless belt 87 is, by any suitable means, stretched taut about the peripheries of the pulleys 85 and 86 in operative contact therewith. To the end last specified two stretcher-frames 90 may be employed. They are supported upon the table 12, as, for example, by arms 91, each of said arms being fixed to the table and being adjustably secured, as by a slot and bolt connection 92, at its opposite ends, to both of the stretcher-frames 90.
- The stretcher-frames 90 are designed to 130

afford true alignment to the belt 87 and to present it in smooth vertical disposition directly above the scales 80. For holding it in vertical position, they are preferably provided along their entire length with overhung flanges 93 (Fig. VIII).

Each end of each stretcher-frame is preferably provided with a bifurcated carrier 94, one for the accommodation between the 10 free ends thereof of a guide-roller 95, and the other for like accommodation of a corresponding guide-roller 96, each carrier being deflected so as to bring the outside of its roller in line with the belt 87 and to afford 15 collectively a stretch of the belt between the two rollers 95 and 96. By this means, adjustment of a stretcher-frame accomplishes operative adjustment of relative disposition of the belt 87 to the scales which it serves. 20 Tables 97 and 98, being in effect transverse extensions of the table 12, are preferably provided at opposite ends of the table 12 (Figure III). The table 97 carries a longitudinally slotted plate 99 which, by the aid 25 of a bolt 100, is adjustable upon the said table. The plate 99, at one end, carries between two jaws a roller 101 that engages the belt 87. One of its functions is to regulate the tension of the belt 87, and is accomplished 30 through the adjustability of the plate 99. Another function is to augment the length of contact between the belt 87 and the pulley 85 so far as to insure a frictional drive of said belt through its engagement with the pulley 85.

The pulleys 85 and 86 divide in effect the series of scales 80 into two sorting sets which, though all the scales are carried upon one sprocket chain 15, operate as independent sorting elements, each set cooperating for that purpose with a stretcher-frame appropriated to it. The conveyor belt 63 makes delivery of articles to one of the said sets at that point at which, by the obliquity 45 of its stretcher-frame 90, the greatest extent of scale is exhibited to wit, a point adjacent to the roller 95. I prefer to provide at said point of delivery of the conveyor belt 63 a short, flexible chute 102 whose free end, 50 lying upon the surface of the sub-posed traveling scales, is rippled by them in their travel, in the same manner as the flexible strip 57 is caused to functionate by the movement underneath it of the rollers 48, as 55 has already been described, with the effect of properly segregating articles discharged from the conveyor belt 63 and depositing them one by one successively into the individual traveling scales 80.

The conveyor belt 67 in passing around the roller 68 discharges into a delivery chute 103 which is bent to conform to the shape and size of the pulley 86, as shown in Figure III and is deflected downwardly, as shown 65 at 104 in Figure I, so as to make discharge

to the second sorting set of scales previously specified.

Near the ends of said sorting sets of the scales, that are furthest removed, respectively, from the discharge end of the conveyor belt 63 and of the chute 103, respectively, I prefer to provide mechanical means for causing a tilting action of the scales at those points as often as they pass said points in their travel. To that end I 75 provide, upon the stable supports on the frame 1, at each of said points an arched deflector-strip 105 (compare Figs. I, III and VIII) in operative proximity to the beams 76 as they travel over it in succession. The 80 presence of the deflector-strip 105 causes the beams to tilt each upon its fulcrum support 75 and thereby insures clearance of any light-weight articles that may remain in the scales. The effect is to convert the last of 85 each series of bins 83 into a cull-bin.

The operation of my machine may be briefly described as follows.

Power being applied to the pulley 4, the several movable elements of the machine are 90 thereby set in motion, each in the direction indicated by arrows in various figures of the drawings.

The hopper 49 is kept supplied with articles, for example apples, intended to be 95 sorted by the machine, and a constant discharge is effected therefrom through the jiggling movement of the bottom 50 imparted to it by the snub action against its free end of successive rollers 48. The articles so delivered to the strip 57 are, by the action of the rollers 48 passing underneath and in contact with said strip, ranged between the rollers and lifted up the incline indicated by the strips 44 over the shaft 40. Thence they 105 are conveyed in a horizontal direction over a purposely extended display stretched toward the cross-strip 59, the extent of the display stretch referred to being provided in order to afford to an attendant opportunity of inspection of the articles therein exhibited, whereby he is enabled to select "seconds" 110 from "prime" articles, and to detect and remove any culs that may present themselves.

The rolling movement of the articles, 115 caused, as has been specified, by the action of the rollers 48 upon them, communicated through the strip 57, tends to exhibit to the eye of the attendant all sides of an article so as to expose imperfections, if any.

The selecting and culling office is performed by an attendant stationed on one side of that portion of the machine shown in Figure IV, and is intended to be performed mainly during the travel of articles in 125 passing over the display stretch that extends between the shaft 40 and the cross-piece 59. My machine makes it possible to adopt the rule of inspection that the attendant shall select from the articles so 130

exhibited only "seconds" and defective articles, and leave the sorting of the "prime" articles entirely to the work of the machine, which is in consequence made 5 to do the work which several men were heretofore required to do. The "seconds" he deposits upon the conveyor belt 67 between the guard rails 70 and 71. Defective articles are cast into the cull-chutes 10 73 and 74, a plurality of chutes being provided for effecting the grading of the culs if desired.

It is designed, in accordance with the rule 15 of selection just indicated, that only prime articles shall be delivered to conveyor belt 63, by which selection is automatically accomplished by the machine through the sweeping function of the obliquely disposed cross-strip 59. Articles delivered to the conveyor belt 63 are designed to pass in regular succession one by one to the sorting set 20 of scales presented, as shown in Figure III, at the discharge end of the conveyor belt 63, that is the bend thereof about the roller 64. The flexible delivery chute 102 is designed 25 and adapted, as has been specified, to insure delivery of the articles to be sorted one by one in regular succession to the traveling series of scales. If, for example, an article 30 above an established critical weight be delivered to the scale next adjacent to the flexible delivery chute 102 in Figure III, it will immediately tilt the scale and drop the article into the bin 83 below it. If, on the 35 other hand, the article be of a weight inferior to the critical, it will be carried by the movement of the scale which holds it, in contact with the face of the vertical belt 87, by whose obliquity it will be gradually 40 pushed towards the free end of said scale. By this means it will be carried in the travel of its containing scale to a point at which its weight will be sufficient to overbalance the counterpoise 81 of its scale, when 45 the beam 76 will tilt, with the effect of discharging the article from the scale into that bin which happens to be below. The synchronized movement of the belt 87 and of the sprocket chain 15 effects a stability of 50 disposition of the article through its travel endwise of the scale, and eliminates possibility of the tilting of the scale in consequence of any adventitious motion imparted to the article. The oblique disposition of 55 the stretcher-frame 90 is designed to effect discharge of all articles from the largest to the smallest before the travel on the scales in the direction of the roller 96 is completed, but absolutely to insure such discharge, the deflector plate 105, operating as 60 has been previously specified, is preferably provided.

"Seconds" deposited upon the conveyor belt 67, as has been specified, are conveyed 65 by it to the chute 103 and are thence dis-

charged to the second sorting set of scales where the said "seconds" are sorted in like manner as the "primes" are sorted, and are distributed in like manner to the several bins 83 that are provided for the reception 70 of "seconds."

What I claim is:

1. In a sorting machine, the combination with a series of pivotally fulcrumed parallel balance members adapted, respectively, 75 to receive individual articles to be sorted by weight, and a counterpoise for each member, of means operative successively upon the article carried by the respective members for effecting the overbalancing of each 80 counterpoise, one by one, with tilting discharge effect upon its balance member.

2. In a sorting machine, the combination with a series of pivotally fulcrumed balance members adapted, respectively, to receive individual articles to be sorted by weight, of 85 means for imparting motion, severally, to said articles with reference to the longitudinal axis of said members, and thereby causing discharge of said members through the 90 tilting of the same upon their respective fulcrums.

3. In a sorting machine, the combination with a series of pivotally fulcrumed balance members, of means for imparting motion to 95 said members in series, and means operative by the movement of said series to impart motion to articles carried individually by said members and thereby to cause the same to tilt and discharge their respective loads, 100 for the purpose specified.

4. A sorting machine comprising a series of pivotally mounted scales, a counterpoise for each scale for holding it normally horizontal, means for imparting motion to the 105 series, and means for gradually moving the contents of each scale so as to overbalance its counterpoise and to tilt the scale for the discharge of its contents.

5. A sorting machine comprising a series 110 of pivotally mounted scales, a counterpoise for each scale for holding it normally horizontal, means for imparting motion to the series, means for gradually moving the contents of each scale so as eventually to overbalance its counterpoise and tilt the scale, and means for feeding articles to the scales. 115

6. A sorting machine comprising a series of pivotally mounted scales, a counterpoise for each scale for holding it normally horizontal, means for imparting motion to the series, means for gradually moving the contents of each scale so as eventually to overbalance its counterpoise and tilt the scale, means for feeding articles to the scales, and 120 a series of separate bins for receiving the sorted articles from the scales. 125

7. A sorting machine comprising a series of pivotally mounted scales, a counterpoise for each scale for holding it normally horizontal, 130

- zontal, means for imparting motion to the series, means for gradually moving the contents of each scale so as eventually to overbalance its counterpoise and tilt the scale, 5 said last named means consisting of a member obliquely disposed in the path of movement of the series.
8. A sorting machine comprising a series of pivotally mounted scales, a counterpoise 10 for each scale for holding it normally horizontal, means for imparting motion to the series, means for gradually moving the contents of each scale so as eventually to overbalance its counterpoise and tilt the scale, 15 said last named means consisting of a member obliquely disposed in the path of movement of the series and traveling in the direction of their serial movement.
9. A sorting machine comprising a series 20 of pivotally mounted scales, a counterpoise for each scale for holding it normally horizontal, means for imparting motion to the series, means for gradually moving the contents of each scale so as eventually to overbalance its counterpoise and tilt the scale, 25 each counterpoise being adjustable longitudinally with respect to its scale.
10. A sorting machine comprising a series 30 of scales, an endless belt for supporting the scales and to which the scales are pivoted, means for supplying articles to the scales, one by one, at one end of said belt, a series of bins disposed alongside said belt and adapted to receive discharge from the scales, a 35 counterpoise on each scale for normally holding it approximately in horizontal position, and means for gradually moving the contents of each scale outwardly away from its counterpoise as the scales move away 40 from the feeding end by motion imparted to them through movement of the endless belt.
11. A sorting machine comprising a series 45 of scales for the reception of individual articles to be sorted, means for supporting the scales and moving the series, a counterpoise for each scale for normally holding it in horizontal position, and means for gradually moving the contents of each scale to cause 50 the weight of its contents to tilt the same upon its pivotal support.
12. A sorting machine comprising a series 55 of counterpoised pivotally mounted scales, an endless belt for supporting the scales and moving the series, another endless belt obliquely disposed in operative relationship to and above said series of scales, and means for imparting to both belts synchronous motion in the same direction.
- 60 13. A weight controlled sorting machine, comprising a pivotally mounted, normally horizontal support for each individual article to be sorted, means for moving the support, and means for gradually moving an 65 article on the support away from the pivotal connection of the support, and thereby to cause the support to tilt when the movement of the article thereon overcomes the equilibrium of the support.
14. In a weight controlled sorting machine, a pivotally mounted, normally horizontal support for each individual article to be sorted, and means for gradually moving the article on the support away from the pivotal connection thereof to cause the support to tilt and discharge the article. 70
15. A weight controlled sorting machine, comprising a pivotally mounted support for each individual article to be sorted, means for moving the support, means for normally holding the support in horizontal position, and means for moving the article on the support away from the pivotal connection thereof to cause the support to tilt. 75
16. The combination with a sorting machine comprising an endless series of individual article supports movable in series, and means for discharging the supports one by one, of a conveyor belt comprising an inclined stretch constituting feed mechanism 80 to said machine, and means for operating it. 90
17. The combination with a sorting machine comprising an endless series of individual article supports movable in series, and means for discharging the supports one by one, of a conveyor belt constituting feed mechanism to said machine, and a flexible chute intermediate the discharge end of said belt and the machine. 95
18. The combination with a sorting machine comprising an endless series of individual article supports movable in series, and means for discharging the supports one by one, of a conveyor belt constituting feed mechanism to said machine, a second conveyor belt in available proximity to the one first named for the transfer of articles removed by an operator from one belt to the other. 100
19. In a sorting machine, the combination 110 with a frame, driving mechanism, and an endless belt carrying a series of normally horizontal counterweighted supports, one for each individual article to be sorted, of means for gradually moving said articles on the supports, respectively, away from the pivotal connection of the support, for the purpose specified, said means consisting of an endless belt disposed above and in operative proximity to said series of supports. 115
20. In a sorting machine, the combination 120 with a frame, driving mechanism, and an endless belt carrying a series of normally horizontal counterweighted supports, one for each individual article to be sorted, of means for gradually moving said articles on the supports, respectively, away from the pivotal connection of the support, for the purpose specified, said means consisting of an endless belt disposed above and in operative 125 proximity to said series of supports. 130

proximity to said series of supports, and means for driving both endless belts substantially at equal speeds.

21. In a sorting machine, the combination with a frame, driving mechanism, and an endless belt carrying a series of normally horizontal counterweighted supports, one for each individual article to be sorted, of means for gradually moving said articles on the supports away from the pivotal connection of the support, said means consisting of an endless belt disposed above and in opera-

tive proximity to said series of supports, and stretcher frames for the guidance of the last named belt with reference to said series 15 of supports.

In testimony whereof, I have hereunto set my hand in the presence of two subscribing witnesses.

TIMOTHY NEWELL.
